UNITED STATES PATENT OFFICE.

PAUL MORÀLES DAVIS, OF BROOKLYN, NEW YORK.

DESIGN FOR A TOY.

50,238.

Specification for Design. Patented Jan. 30, 1917.

Application filed November 18, 1916. Serial No. 132,228. Term of patent 3½ years.

To all whom it may concern:

Be it known that I, PAUL MORÀLES DAVIS, a citizen of the United States, residing in the city of New York, borough of Brooklyn, in the county of Kings and State of New York, have invented a new, original and ornamental Design for a Toy, of which the following is a specification, reference being had to the accompanying drawing, forming part thereof.

The figure is a perspective view of a toy, showing my new design.

I claim:

The ornamental design for a toy, as shown.

PAUL MORÀLES DAVIS.

Witnessed by—

JAMES J. CORBETT.
